United States Patent Office

Des. 181,856
Patented Jan. 7, 1958

181,856

CAN PUNCH

Eric W. Johnson, Thrall, Tex.

Application April 8, 1957, Serial No. 45,641

Term of patent 14 years

(Cl. D44—29)

Fig. 1 is a side elevational view of a can punch showing my new design;

Fig. 2 is a top plan view thereof;

Fig. 3 is a side elevation of the reverse side of the can punch; and

Fig. 4 is an end view thereof.

I claim:

The ornamental design for a can punch, as shown.
